(57) **CLAIM**

The ornamental design for an electric bicycle frame as shown and described.

DESCRIPTION

1.1 is a front and left side perspective view of an electric bicycle frame embodying our new design;

1.2 is a rear elevation view thereof;

1.3 is a front elevation view thereof;

1.4 is a left side elevation view thereof;

1.5 is a right side elevation view thereof;

1.6 is a top plan view thereof; and

1.7 is a bottom plan view thereof.

The broken lines in the drawing depict portions of the electric bicycle frame that form no part of the claimed design.
